APPARATUS FOR DRYING MATERIALS IN PASTE FORM

Stanislaus Bogaty, Philadelphia, Pa., assignor to Proctor & Schwartz, Inc., Philadelphia, Pa., a corporation of Pennsylvania

Application October 21, 1953, Serial No. 387,490

4 Claims. (Cl. 34—225)

This invention relates to new and useful improvements in apparatus for drying materials in the form or consistency of paste.

The principal object of the present invention is to provide a novel method for drying materials in paste form which is efficient, and both economical and practical for commercial production requirements.

Another object of the invention is to provide a novel apparatus for carrying out the method.

These and other objects of the invention and the various features and details of the construction and operation thereof are hereinafter fully set forth and described with reference to the accompanying drawings, in which:

Fig. 1 is a plan view of apparatus embodying the present invention for drying materials in paste form and consistency in accordance with the method of the present invention, a portion of the top of the dryer having been cut-away to illustrate certain details of the construction;

Fig. 2 is a side elevational view of the disclosure in Fig. 1;

Fig. 3 is an enlarged sectional view taken on line 3—3, Fig. 1; and

Fig. 4 is an enlarged sectional view taken on line 4—4, Fig. 3.

In accordance with the present invention the material to be dried is deposited in the form of a relatively plastic or viscous mass or paste in a plurality of continuous ribbons 1 upon an endless conveyor 2 of heat-conducting material such as, for example, stainless steel of sufficiently thin gauge to render it flexible and enable it to pass about the usual rolls or pulleys on which endless conveyors customarily are mounted. The ribbons 1 of the material extend longitudinally of the conveyor upon and are disposed in spaced parallel relation transversely thereof.

The ribbons 1 of the material are dried by passing them through drying apparatus, generally designated 3, which is constructed and operable in accordance with the present invention. Referring to the drawings, the drying apparatus 3 of the present invention comprises a housing or enclosure 4 including top wall 5, opposite end walls 6 and 6a and opposite side walls 7 and 8, respectively. The conveyor 2 with the ribbons 1 thereon enters the dryer 3 at the lefthand end thereof with respect to Fig. 1 of the drawings and emerges from the dryer at the righthand end thereof.

The interior of the dryer 3 is sub-divided by transverse vertical partitions 9 and 10 into three substantially identical sections A, B and C of the dryer 3 in overlying relation to the conveyor 2 is a hood structure 11. As shown in Fig. 3 of the drawings, in each section the hood 11 is in the general form of a truncated pyramid which is divergent downwardly from an inlet opening 12 for air at the top thereof to the lower end of the hood which extends longitudinally the full length of the section and

2

has a width transversely of the dryer which is substantially coextensive with the width of the underlying conveyor 2. The hood 11 in each section is supported from a horizontal partition 13.

5 Overlying the top of the hood 11 in each section of the dryer and in communication with the air inlet opening 12 thereto is an air chamber 14 into which air is discharged laterally through control dampers 15 from a fan or blower 16 driven by a suitable motor 17 mounted on the top 5 of the dryer housing. The partition member 13 also supports the air chamber 14 and fan or blower 16.

A vertical partition 18 is mounted below the horizontal partition 13 and extends longitudinally centrally of each section of the dryer to sub-divide the upper portion of 15 the section below the horizontal partition 13 into separate zones for movement of the drying air in opposite directions.

An air inlet port 19 to each of the sections A and B of the dryer is provided in the side wall 8 of the dryer housing and the amount of air admitted to the sections through the ports 19 is controlled by means of louvers or shutters 20. Mounted horizontally in each of sections A, B and C of the dryer and supported between the side wall 8 thereof and vertical partition 18 is a heating element 21 for heating the drying air.

By reason of the construction and arrangement described, air discharged or admitted to the lower portions of the sections rises upwardly between the dryer wall 8 and partition 18, passes through the heaters 21 where the temperature of air is raised to the desired degree. The heated air then continues its upward passage through an opening 13a in the partition 13 to the intake of the fan or blower 16 from which it is discharged laterally and passes through the control louvers or shutters 15 to the air chamber 14. From the chamber 14 the heated air passes downwardly into and through the hood 11 and is discharged from the bottom of the hood through a series of transversely extending narrow elongated nozzles 22 arranged in spaced parallel relation longitudinally of the 40 dryer section. The discharge nozzles 22 may be formed by stamping the same in the bottom plate 23 of the hood 11, for example, as shown in Fig. 4 of the drawings.

As shown, the nozzles 22 are disposed transversely of 45 the conveyor 2 and the direction of travel of the ribbons 1 of the material thereon and the length of the nozzles 22 is such that the nozzles extend coextensive with the width of the said conveyor and entirely overlie the ribbons 1 thereon. By virtue of this construction and arrangement, the heated drying air passing downwardly through the hood 11 is discharged through the nozzles 22 perpendicularly into impinging contact with the upper surface of the ribbons 1. The drying air then flows laterally in opposite directions across the ribbons on the conveyor and downwardly about the lateral edges of the conveyor 2 into the lower portion of the dryer section.

A predetermined portion of the spent drying air in sections A and B is reheated and recirculated in the manner previously described, and the balance is exhausted from 60 the dryer. For this purpose there is provided in the lower portion of each section A and B of the dryer an exhaust duct 24 having inlet openings 25 in the top thereof for the air. The exhaust ducts 24 extend longitudinally beneath the conveyor 2 the entire length of each section A and B, respectively. The exhaust air is conducted from ducts 24 by ducts 26 to an exhaust manifold 27 which extends longitudinally above the dryer housing and has its outlet end connected to the intake of an exhaust fan or blower 28.

70 In some cases, in order to prevent the two outermost ribbons 1 of material adjacent the opposite side edges of the conveyor 2 from drying too rapidly and at a faster

rate than the more inwardly disposed ribbons 1, it has been found desirable to partially reduce or throttle the air discharged from the nozzles 22 directly onto the surface of these outermost ribbons 1. In accordance with the present invention this may be accomplished effectively by partially covering the discharge nozzles 22 adjacent the outermost ribbons 1 only of the conveyor 2, by a perforate baffle or like structure 29. Such a baffle may consist, for example, of one or more thicknesses of screening and in practice satisfactory results have been obtained by employing two thicknesses of 16 mesh screening arranged, for example, as shown in Fig. 3 of the drawings. This construction and arrangement serves to throttle the air discharged from the end portions of the nozzles 22 sufficiently to retard the rate of drying of the outermost ribbons 1 so that they dry at substantially the same rate as the innermost ribbons.

The heaters 21 in each of the sections of the dryer are controlled by conventional temperature-responsive instruments to heat the drying air passing therethrough and provide a suitable drying temperature for the particular material at the discharge nozzles 22. The temperature required in any given case depends upon the speed of travel of the conveyor 2, the consistency and thickness of the particular ribbons of the material being dried and the humidity of the inlet air, higher temperatures being employed in the summer season because of the relatively high humidity conditions existing in that season, and lower temperatures being employed in the other seasons and in periods of relatively low humidity. The construction and arrangement of the fan or blower 16 and the hood 11 is such as to discharge air from the nozzles 22 at high velocity.

In addition to the temperature control provided in each of the sections A, B and C of the dryer, provision is also made for controlling the relative humidity in the central section B. This may be accomplished, for example, by controlling the amount of air exhausted from section B, for example, by means of baffle or shutters 32 provided in the exhaust manifold 27 (see Fig. 2) or by means of a water spray (not shown) mounted within the section. Either such device may be controlled manually or automatically in conventional manner by standard instruments and controls readily available commercially.

In practicing the invention, the material in paste form is deposited upon the conveyor 2 in ribbons 1 having a predetermined depth or thickness and these ribbons are thoroughly dried during passage through successive sections A, B and C of the dryer. In the process of drying, the thickness or depth of the ribbons is reduced. Immediately prior to emerging from the dryer, the steel conveyor may be cooled, for example, by passing it in contact with a chilled or refrigerated roll, for the purpose of removing any tackiness in the dried ribbons and also to shrink the ribbons slightly to facilitate their separation and removal from the conveyor. The dried ribbons of the material are then doctored or otherwise separated from the conveyor 2 and wound upon suitable mandrels according to the conventional practices.

I claim:

1. A dryer for materials in paste form comprising a housing, means subdividing said housing into a succession of drying sections, an endless conveyor passing entirely through the housing and the several drying sections thereof to convey thin layers of the material successively through said sections, a plurality of narrow elongated discharge nozzles for drying air in each section of the dryer overlying the conveyor and disposed in spaced parallel relation lengthwise of the conveyor with the individual nozzles extending transversely thereof, said nozzles being disposed to discharge drying air downwardly perpendicular to the plane of the conveyor, and perforate members disposed in the air stream at the opposite end portions of the discharge nozzles operable to partially

throttle the drying air discharged through said nozzle end portions and thereby retard the rate of drying of the outer portions of the material on the conveyor so that they dry at substantially the same rate as the inner portions thereof.

2. A dryer for materials in paste form comprising a housing, means subdividing said housing into a succession of drying sections, an endless conveyor passing entirely through the housing and the several drying sections thereof to convey thin layers of the material successively through said sections, a plurality of narrow elongated discharge nozzles for drying air in each section of the dryer overlying the conveyor and extending in spaced parallel relation lengthwise of the conveyor with the individual nozzles extending transversely thereof, said nozzles being disposed to discharge the drying air downwardly perpendicular to the plane of the conveyor, means in each section to heat the drying air to a predetermined temperature, means in each section to force the heated drying air through the discharge nozzles at a selected velocity, and baffle means in each section extending longitudinally of the conveyor intermediate the opposite side portions of the conveyor and the overlying end portions of the discharge nozzles to partially throttle the discharged drying air and thereby retard the rate of drying of the outer portions of the material on the conveyor so that they dry at substantially the same rate as the inner portions thereof.

3. A dryer for materials in paste form comprising a housing, means subdividing said housing into a succession of drying sections, an endless conveyor passing entirely through the housing and the several drying sections thereof to convey thin layers of the material successively through said sections, a plurality of narrow elongated discharge nozzles for drying air in each section of the dryer overlying the conveyor and extending in spaced parallel relation lengthwise of the conveyor with the individual nozzles extending transversely thereof, said nozzles being disposed to discharge the drying air downwardly perpendicular to the plane of the conveyor, and baffle means in each section extending longitudinally of the conveyor intermediate the opposite side portions of the conveyor and the overlying end portions of the discharge nozzles to partially throttle the discharged drying air and thereby retard the rate of drying of the outer portions of the material on the conveyor so that they dry at substantially the same rate as the inner portions thereof.

4. A dryer for materials in paste form comprising a housing, means subdividing said housing into a succession of drying sections, an endless conveyor passing entirely through the housing and the several drying sections thereof to convey thin layers of the material successively through said sections, a plurality of narrow elongated discharge nozzles for drying air in each section of the dryer overlying the conveyor and extending in spaced parallel relation lengthwise of the conveyor with the individual nozzles extending transversely thereof, said nozzles being disposed to discharge the drying air downwardly perpendicular to the plane of the conveyor, means in each section to heat the drying air to a predetermined temperature, means in each section to force the heated drying air through the discharge nozzles at a selected velocity, baffle means in each section extending longitudinally of the conveyor intermediate the opposite side portions of the conveyor and the overlying end portions of the discharge nozzles to partially throttle the discharged drying air and thereby retard the rate of drying of the outer portions of the material on the conveyor so that they dry at substantially the same rate as the inner portions thereof, and an exhaust air duct extending longitudinally beneath the conveyor in at least some of said sections, and exhaust means connected to each of said ducts in said sections.
